GEORGE W. HAMBROOK AND WERNER E. CLARIN, OF CHICAGO, ILLINOIS, ASSIGNORS TO
CLARIN MFG. CO., OF CHICAGO, ILLINOIS, A CORPORATION OF ILLINOIS

TABLE LEG LOCK

Application filed October 31, 1931. Serial No. 572,289.

This invention relates to the art of collapsible tables, such as card tables, that are commonly constructed with inwardly foldable hinged legs, and the invention has reference more particularly to an improved device for automatically locking the legs in fully extended position, when the table is to be used.

The principal object of the invention has been to provide a very simple, strong and reliable table leg lock, which will automatically lock the leg in extended position when the table is upright, and will automatically unlock the leg when the table is laid on its side or inverted, thus doing away with the necessity of hand manipulated lock devices at present extensively employed.

Our invention, its manner of use, and the advantages inherent therein will all be readily understood by persons familiar with tables of this type from the following detailed description, taken in connection with the accompanying drawing, in which we have illustrated one simple and approved embodiment of the invention, and wherein:—

Fig. 1 is a vertical section through the corner of the table and the upper portion of the leg, showing the latter in extended or operative position, and locked.

Fig. 2 is a similar view, showing the leg unlocked and folded beneath the top of the table.

Fig. 3 is a vertical section in a plane at right angles to that of Figs. 1 and 2, on the line 3—3 of Fig. 1.

Fig. 4 is a perspective detail of a member which forms the inner end and bottom walls of a housing in which the leg is pivoted.

Fig. 5 is a perspective detail of a keeper for the gravity-actuated locking member designed to prevent its accidental escape.

Referring to the drawing, 10 designates a corner portion of the flat table top, which preferably is of sheet steel. Attached to the under side of the corner portion of the table top, as by cap screws 11, is a corner bracket, preferably taking the form of a hollow housing comprising parallel side walls 12, an outer end wall 13, an inner end wall 14, and a bottom wall 15. The inner end wall 14 and bot-

tom wall 15 are conveniently made in a single structure shown in detail in Fig. 4, the upper end of the wall 14 having an integral attaching flange 16 and tapped holes 17 to receive cap screws 18 by which it is secured to the bottom of the table top. The bottom wall 15 is united to an inwardly directed flange 19 on the lower end of the outer end wall 13 as by a cap screw 20. This bottom wall 15 of the housing is formed with a hole 21, the function of which will later appear.

22 designates a hollow metal table leg, that is formed with a forked upper end, the parallel limbs of the fork being designated by 23. These limbs 23 are entered from beneath into the housing, lying against the inner sides of the side walls 12, and hinged to the latter by a pivot pin 24. At the base of the forked upper end portion of the leg is a transverse wall 25 that is formed with a depressed ball seat 26. The member forming the bottom and inner end wall of the housing is sufficiently narrower than the distance between the side walls 12 to permit play of the limbs 23 of the forked end of the leg when swinging the latter between folded and extended positions.

Confined within the housing is the freely movable gravity-actuated locking member, which preferably takes the form of a steel ball 27. This ball is of slightly less diameter than the hole 21, and fits the seat 26, so that when the leg 22 is extended at right angles to the table top, and the table is in upright position, the ball comes to rest in the hole 21 and seat 26, with the lower edge of the hole 21 slightly above the horizontal plane of the center of the ball, as shown in Fig. 1, whereby the leg is securely locked against swinging in either direction.

Since, in the construction shown, the hole 21 is large enough to permit the ball to pass therethrough, means must be provided to prevent escape of the ball when the leg has been folded to a position carrying the seat 26 beyond the hole 21. The means herein shown for this purpose consists of a keeper member mounted in the upper forked end of the leg which receives and retains the ball when the leg is folded. This keeper member,

shown in isolated detail in Fig. 5, preferably comprises a transverse wall 28 formed with oppositely disposed upwardly extending limbs 29 apertured to fit the pivot pin 24, and 5 a pair of depending oppositely disposed limbs 30 which, with the transverse wall 28, form a pocket having its open end facing the ball seat 26. The keeper member is locked to the forked extension of the leg so as to swing 10 with the latter by a cross pin 31 extending through the limbs 29 and also the limbs 23 of the leg.

To fold the leg from the extended position (Fig. 1) to the folded position (Fig. 2), 15 the table is laid on its side, and the leg tilted slightly above the horizontal. The ball 27 at once rolls out of its seat, through the hole 21, and into the pocket. The leg is then 20 swung inwardly with the ball in the pocket, and when the open end of the pocket has 25 passed out of register with the hole 21, the ball is trapped in the pocket by the opposed inner end wall 14 of the housing, which latter, it will be observed, is curved substantially on an arc struck from the axis of the pivot pin 24. To unfold the leg, the table is preferably 30 laid on its side, the leg is swung outwardly, bringing the open end of the pocket into register with the hole 21, and when the table 35 is raised to upright position, the ball automatically drops into locking position.

The device thus does away with the necessity of separate manual locking and unlocking devices, requiring only the placing of the 35 table in a favorable position to allow the locking ball to move by gravity into and out of a locking position; the ball at all times being itself locked against escape from the housing by the keeper member.

40 While we have herein shown and described one specific form of the invention, which, in practice, has been found to satisfactorily effectuate the stated purpose or object, we do not limit the invention to the details of structure and arrangement shown, but reserve all 45 such variations, modifications and mechanical equivalents as fall within the spirit and purview of the claims.

We claim:

50 1. The combination with a table top, of a housing attached to and beneath said top formed with a hole in a wall thereof, a leg pivoted on said housing formed with a ball seat registering with said hole in the extended 55 position of the leg, and a gravity-actuated ball adapted to occupy said hole and seat in the upright position of the table to thereby lock said leg in extended position.

2. The combination with a table top, of a 60 housing attached to and beneath said top formed with a hole in its bottom wall, a leg pivoted on said housing formed with a seat for a locking member below and registering with said hole in the extended position of the leg, a gravity-actuated locking member in

said housing of slightly less diameter than said hole, and a keeper preventing escape of said locking member through said hole when the leg is folded.

3. The combination with a table top, of a 70 housing attached to and beneath said top formed with a hole in its bottom wall, a leg pivoted on opposite sides of said housing formed with an internal seat for a locking member below and registering with said hole in the extended position of the leg, a freely 75 movable gravity-actuated ball in said housing of slightly less diameter than said hole, and a keeper preventing escape of said ball through said hole when the leg is folded. 80

4. The combination with a table top, of a 85 housing attached to and beneath said top formed with a hole in its bottom wall, a leg having a forked upper end portion pivoted within and on opposite sides of said housing, 90 said leg formed with an internal seat for a locking member below and registering with said hole in the extended position of the leg, a freely movable gravity-actuated locking member in said housing of slightly less diameter 95 than said hole, and a keeper mounted in the upper forked portion of said leg serving, in cooperation with a wall of said housing, to trap and prevent escape of said locking member through said hole when the leg is folded. 100

5. The combination with a table top, of a 105 housing attached to and beneath said top formed with a hole in its bottom wall, a leg having a forked upper end portion pivoted within and on opposite sides of said housing, 110 said leg formed with an internal ball seat below and registering with said hole in the extended position of the leg, a gravity-actuated ball in said housing of slightly less diameter than said hole, and a keeper rigidly mounted in the upper formed portion of said leg, said keeper formed with a downwardly opening pocket adapted to trap and prevent escape of said ball through said hole when the leg is folded. 115
